UNITED STATES PATENT OFFICE.

JOHN A. PRICE, OF SCRANTON, PENNSYLVANIA.

STOVE OR RANGE.

SPECIFICATION forming part of Letters Patent No. 321,527, dated July 7, 1885.

Application filed March 29, 1883. (No model.)

To all whom it may concern:

Be it known that I, JOHN A. PRICE, of Scranton, in the county of Lackawanna and State of Pennsylvania, have invented certain new and useful Improvements in Stoves or Ranges; and I do hereby declare the following to be a full, clear, and exact description of the same, reference being had to the accompanying drawings, forming a part of this specification, to and to the figures and letters of reference marked thereon.

This invention consists in certain novel improvements in stoves and ranges, whereby a great proportion of the heat which passes off from the top of the stove or range, as well as that which passes up the smoke-flue, is directed into an elevated closet and there utilized for baking and warming purposes.

In the accompanying drawings, Figure 1 represents a front view of a range with my improvements applied thereto. Fig. 2 is a longitudinal vertical section of the same. Fig. 3 is a bottom plan view of the elevated hot-closet.

Similar letters of reference in the several figures indicate the same parts.

A represents the top of the range; B, a horizontal box or flue communicating at the front with the smoke-discharge opening C in the range top, and at the rear with a vertical smoke-flue, D.

A damper, E, is provided in the forward part of box B, and a depression or receptacle, F, is formed in its bottom at the rear for the accumulation of soot falling in the flue D, and a removable cover, G, is provided at the end of the depression or receptacle, so as to enable said depression to be cleaned out when necessary.

H represents an elevated hot-closet, preferably lined with asbestos, mineral-wool, clay, terra-cotta, or other like material, and having doors H' H', which permit access to the interior from the front.

A flue, I, leads from the vertical smoke-flue D to the bottom of the hot-closet H, near the middle thereof, and another flue, J, leads from the top of said closet back to the flue D again, all as shown in Fig. 2. Both flues I and J lead into the hot-closet through openings i and j, respectively.

K is a valve, located in pipe D and adapt-

ed to be turned so as to close flue D or the entrance to flue I, as desired; and L is another valve, adapted to open or close exit-flue J. 55

It will be apparent from this construction that when the valves are turned so as to leave both the lower and upper flues, I J, open, the heat from the range fire ascending the flue D will be directed into and through the hot-closet 6c and there utilized for baking meats, bread, and other food, or for keep hot food already cooked. By manipulating the valves K L more or less heat can be admitted into the closet, and a greater or less amount of circulation of heated 65 air therein can be maintained. When once thoroughly heated, all communication with the flue D can be cut off, and the closet, lined as aforesaid, will retain the heat for a long time. 70

The bottom M of the closet I preferably slot, as shown in Fig. 3, on each side of the opening leading to flue I, and combine with it one or more laterally-moving register-slides, N N. When the slides are drawn outward, 75 as shown in Fig. 3, the slots or openings in the bottom are uncovered, and the heat rising from the top of the range passes up into the closet and is there utilized. The opening of the upper valve, L, more or less facilitates 80 this result.

When the register in the bottom of the oven is open, and the valve in the flue leading from the oven is also open, the heat rising from the stove will enter the oven and warm or heat 85 any articles therein; but if this heat should not prove sufficient, the valve in the lower flue may be opened so as to permit more or less direct heat to pass from the vertical flue into and through the oven back to said vertical 90 flue. Again, both valves may be opened and the bottom register closed while the article in the oven is being cooked. Now, if the heat in the oven gets too great, and a slower action is desired, the bottom of the oven may be 95 opened by moving the register, and thus by admitting the air which rises from the top of the stove, and which is necessarily of lower temperature than that passed directly into the oven from the smoke-exit pipe, render the 100 oven "slower."

This provision of the slotted closet bottom covered by register-slides in connection with the upper and lower flues I regard an impor-

tant improvement, as it enables me to utilize heat which is ordinarily wasted.

As a means for operating the slides N N, I preferably employ two rods, N' N', projecting laterally from each of them in substantially the same plane, and connected by a third rod, O, which is hinged to one of them and adapted to rest within a depression or hook, n, of the other, as shown in Fig. 3. By grasping the rods O the slides can be moved in or out, and by disengaging them from their recesses n and turning them outward, as indicated by the dotted lines, Fig. 3, they can be made to serve as towel or cloth holders.

15 Having thus described my invention, I claim as new—

1. The combination, with the stove or range and the vertical smoke-pipe, of the elevated hot-closet projecting over the top of the stove or range and having a flue leading from within it to and into the smoke-pipe, and having also a grated bottom covered by a valve which can be opened to admit the heat and gases rising from the stove or range top and conduct 20 the same directly through the closet into the smoke-pipe, substantially as described.

2. The combination, with the stove or range, of the elevated hot-closet, the vertical heat and smoke flue, a flue leading out of the vertical flue and opening directly into the hot-closet, and another flue leading directly out of the hot-closet back into the vertical flue, whereby the heat passing up the vertical flue 30 may be conducted directly through the hot-closet and back again into the vertical flue, substantially as described.

3. The combination, with the stove or range, of the elevated hot-closet, the vertical heat and smoke flue, a lower flue leading out of the vertical flue and opening directly into the hot-closet, and an upper flue leading directly out of the hot-closet back into the vertical flue, and valves for controlling the passage of hot air through said upper and lower flues, substantially as described. 40

4. The combination, with the stove or range, of the elevated hot-closet having the grated bottom provided with the adjustable slides or valves, of the vertical heat and smoke flue, the lower flue leading out of the vertical flue and 45 opening directly into the hot-closet, and the upper flue leading out of the closet back into the said vertical flue, and valves for controlling the upper and lower flues, whereby more or less heat can be conducted from the vertical flue directly through the hot-closet, and whereby, also, at the same time more or less of the heat arising from the range top can be conducted through the hot-closet, substantially as described. 50

5. The handle of the adjustable register-slide, consisting of the two rods projecting in substantially the same plane and the third rod hinged to one of said rods and adapted to rest in a depression in the other, or to be swung 55 out so as to serve as a towel or cloth holder, substantially as described.
